LATCH AND HANDLE MECHANISM

Lloyd Anderson, Rockford, Ill., assignor to National Lock Co., Rockford, Ill., a corporation of Delaware

Application April 27, 1937, Serial No. 139,131

11 Claims. (Cl. 292—64)

This invention pertains to latches and operating mechanism therefor.

Among its important objects the invention includes the provision of a latch of general application and especially suited for use with utility closures and cabinets, such, for example, as refrigerators and like devices having automatically opening doors.

A further object is a latch having a bolt normally locked in latching position by a special operating mechanism and a novel easy-release handle coöperable therewith to release or unlock the bolt, and the bolt being thereafter moved into ineffective position by opening of the door, either automatically or otherwise.

A further object of the invention is the provision of a latch having a bolt normally locked in effective position and having mechanism operable to free the bolt for movement into ineffective position, the bolt being moved into such position by the opening of the door or closure with which it is associated.

Still another object is an automatic handle structure coöperable with the aforementioned latch to unlock or release the latter, the handle being of the easy-release type and operable by a light pressure applied thereto in any one of several directions.

Still another object is the provision of a latch of the character described and having a bolt arranged for sliding as well as pivotal movement into and out of effective position, the latch bolt, when released, being pivoted momentarily out of effective position by opening the closure with which it is associated, and the latch bolt also being momentarily slid or cammed into ineffective position by engagement with a strike plate when the door is closed.

A still further object is a compact, rugged and efficient latch structure of the type hereinbefore characterized, and provided with an easy-opening handle device for use on a door having automatic spring mechanism effective to open the door as soon as the latch bolt is freed or unlocked for its automatic operation by the opening movement of the door.

Other novel aspects and objects of the invention will appear as the following description develops in view of the annexed drawings in which like reference characters refer to like parts throughout, and in which:

Fig. 1 is a front elevation of a door and the automatic easy-release handle device thereon, the automatic hinge and latch device being shown in dotted line;

Fig. 2 is a horizontal section through the automatic hinge and taken along lines 2—2 of Fig. 1;

Fig. 3 is a horizontal section through the lower or thrust hinge and is taken along lines 3—3 of Fig. 1;

Fig. 4 is an enlarged horizontal section through the handle structure and is taken along lines 4—4 of Fig. 1;

Fig. 5 is a vertical sectional fragment through the handle and door, and is taken along the jog 10 line 5—5 of Fig. 4;

Fig. 6 is a vertical section through the handle along lines 6—6 of Fig. 4, and indicates in dotted lines two of the several operating positions which the handle can assume;

Figs. 7 and 8 are complementary vertical detail views, respectively, of the rear of the handle and the latch mechanism, each in operative position relative to the other, and Fig. 7 being taken along lines 7—7 of Fig. 5;

Fig. 9 is a vertical section through the latch, and is taken along lines 9—9 of Fig. 8;

Fig. 10 is a top plan view of the latch viewed in the direction of lines 10—10 of Fig. 8;

Fig. 11 is a horizontal section through the latch 25 just above the bolt, and is taken along lines 11—11 of Fig. 8;

Fig. 12 is a horizontal median section through the latch along lines 12—12 of Fig. 8; while

Fig. 13 is a horizontal section similar to Fig. 12, 30 and shows the bolt and spring receded by camming action of the keeper.

Referring to Fig. 1, the novel latch 15 and handle 16 are mounted on the door 17 of a refrigerator having spring-operated, automatic-opening hinge mechanism 18 and 18'. In its operation, the handle 89 may be pivoted up or down, or pulled outwardly of the door, to release the latch device 15, whereupon the door 17 will at once be swung open by the hinge mechanism 18.

Describing first the novel latch with particular reference to Fig. 8, the same is seen to include a housing or jacket 20 of substantially U-shaped cross section and provided with oppositely extending mounting flanges 21 through which are extended screws attaching the latch over a base-plate to the inside of the door 17, the latch housing being open at its ends, and having at one (right-hand) of these ends a pair of diverging 50 wings or tabs 24 and 24' struck out from the opposite side walls of the housing. The upper one of these latter side walls has an open-ended slot or cut-away portion 25 (Fig. 10) adjacent its rear edge and the ear 22. A base plate 26 is po- 55

sitioned between the back of the housing and the door 17 (Figs. 9 and 10), and has an upturned ear 22 having an inwardly directed spring-engaging boss 23.

5 The latch bolt structure includes a sliding bolt carriage 27 of substantially U-shaped or channel-shaped section (Figs. 9 and 11) and fitted within the channel part of the housing 20 with its open ends facing the open ends of the housing, and its 10 open side or top facing the bottom or outer part 20 of the same. This bolt carriage 27 also has an open-ended slot 28 communicating with its rearward upper edge and normally underlying and aligned with the slot 25 in the housing (Fig. 10), 15 while the top free edge portions of the carriage opposite its bottom are bent in to provide gliding flanges 29 (Fig. 9).

From the bottom of the bolt carriage is struck inwardly a spring-retaining ear 30 (Figs. 9 and 20 11) having a boss like the boss 23 on the base plate ear 22, and in the assembly shown in Fig. 13, for example, a moderately strong compression spring 31 is expanded between the ear 22 on the base plate and the ear 30 on the bolt carriage, urging 25 the latter to the right and into the position seen in Fig. 10, this outward movement being limited by an inwardly extending stopping boss 32 struck up from the base plate 26 (Fig. 12) at a point spaced inwardly from its right-hand edge.

30 The right-hand edge of the bottom of the bolt carriage is inset or cut away, as at 33, to a depth just beyond the stopping boss 32 when the right end of the carriage 27 is flush or even with the right edge of the housing 20, the stopping boss 35 being raised sufficiently to confront this edge and limit movement of the carriage toward the right.

A latch bolt 34 (Figs. 8 and 11) having a cam surface 35 has a pair of spaced arms 36 which extend laterally away from the side of the bolt, 40 and these arms 36 have registered openings through which is extended a pivot pin 37 disposed between the sides of the carriage 27. A latch-return spring 38 embraces the pin 37 between the 45 yoke-like arms 36 of the bolt, and one end of this spring bears against an inner end of the bolt, while the opposite end bears against the carriage 27 so as to pivot the bolt into effective position, that is to say, into a position protruding from, and substantially co-extensive with, the carriage. Thus, 50 it will be evident in Fig. 13 that the bolt is urged in an anti-clockwise direction by the spring 38 and may be pivoted in a clockwise direction out of the way of the keeper and back into the carriage.

Pivotedly mounted on a pin 40 within the carriage and at an end opposite the bolt, is a U-shaped latch member 41 having a pair of yoke arms 42 (see particularly Figs. 8 and 11) disposed on its inner side nearest the bolt, and mounted 55 between these arms 42 is a roller 43. A coil spring 44 around the pin 40 normally urges the latch member and roller in an anti-clockwise direction with the roller bearing against an inner latching part or surface 45 on the bolt 34.

60 It will be observed that the pins 37 and 40 about which the bolt and latch, respectively, pivot, are not in alignment, and that in its normal position, as seen for example in Figs. 9 and 12, the vertical body or bight part of the latch bears against the 65 riding flanges 29 as at 39, thus rendering it impossible to pivot the latch member 41 in an anti-clockwise direction, which in turn renders it impossible to pivot the bolt 34 in a clockwise direction, since any attempted pivoting of the bolt in 70 this latter direction tends to pivot the roller and

latch in the opposite direction against the flanges 29.

However, by pivoting the latch in a clockwise sense, the roller 43 will be moved out of the path 5 of the end part 45 of the bolt, which thereupon may be pivoted back into the carriage within the housing, it being recalled also that the carriage 27 may itself be pushed back into the housing against the spring 31 with the same result.

Extended upwardly through the cut-away parts 10 or slots 25 and 28 from the latch member is an operating finger or pin 46 (Figs. 8, 10, 11) which is engageable by a laterally extending arm or finger 47 on a sleeve 48 adjustably attached to the lower end of a vertical operating rod 60. At its 15 lower axial end, the sleeve 48 is fitted upon a stud 61 secured to the top of the housing near the wing 24.

An adjustable connection between the sleeve 20 and rod is effected in a simple manner by means of a pair of screws 62 and 63, each having tapered or conical head portions 64, and each threaded radially into the rod 60 through over-sized holes 65 (Figs. 8 and 10) circumferentially displaced from each other in a direction around the sleeve. 25

Serving to rotate the rod 60 in an anti-clockwise direction into a normal position, and also serving as part of the above-mentioned novel adjustment feature, is a coil spring 66 embracing sleeve 48 at its lower end and having one extremity 67 bent around the arm 47, while its opposite end 68 is bent around a twisted ear portion 69 of the upper integral wing 24 on housing 27. Thus a constant torsional effort is exerted on the sleeve 48 tending to turn it in an anti-clockwise sense 30 relative to rod 60, and when the adjusting screws 62 and 63 are loosened, the sleeve will turn in this sense on the rod 60 until the shank of the screw 63 bears against the side of its corresponding hole 65 in the sleeve. Adjustment is effected by tightening the screw 63 until the tapered shoulder part thereof cams against the side of its corresponding sleeve-hole and rotates the sleeve (clockwise) 35 against the tension of the coil spring 66. This rotation will cause the arm 47 to approach the 40 operating pin 46, and when the desired spacing is 45 achieved, the remaining set screw 62 may be tightened to hold the sleeve 48 rigidly in place on rod 60.

At its upper and headed end, the rod 60 is 50 engaged and supported for pivotal movement by an offset arm 70 of a bracket 71 attached to the rear of the door 17, and the rod has a second or upper and radial finger or handle-engaging arm 72 provided with a hook or pin part 73 for operating 55 engagement with a handle member.

Thus, referring to Figs. 7 and 8, it will be apparent that if the rod 60 is pivoted from left to right or clockwise, the offset finger 70 will bear 60 against the pin 46 and the latch bolt will be freed 65 for subsequent pivotal movement by some other agency.

In Figs. 8 and 10, the latch and bolt are in 70 normal locking position, while in Fig. 11 the rod 60 has been turned to free the bolt and the latter has been pivoted back into its housing by the keeper 75 and particularly by the nose portion 76 thereof, the door 17 being automatically swung out in the direction of the arrow by the spring hinge.

It will be observed that the keeper has a sloped strike plate 77, and when the rod has been freed for return to normal by its spring 66 so as to reposition the roller 43 and latch the bolt, the bolt 34 can no longer be pivoted. 75

If now the door 17 be swung closed in the direction of the tracer arrow in Fig. 13, the cam surface 35 of the bolt 34 will bear against the cam face 77 of the strike plate and the entire bolt carriage 27 and bolt 34 will recede into the housing 20 against the compression spring 31 until the bolt can pass the nose 76 of the keeper, whereupon the bolt will quickly slide back into the keeper 75 behind the keeper nose 76.

10 Of great importance in the operation of the aforesaid latch is the easy-release mechanism by means of which the novel latch is operated, and which includes the movable handle member 80, and a pair of stationary handle mounts 81 and 82 (Figs. 1 and 4), secured to the door.

The handle portion 80 is preferably in the form of an arcuate hollow-cast body having a rear cover plate 83 screwed into place thereon and provided with firm-grip undulations 84. At 20 the right end of the handle body 80 is a projection 85 having a ball formation 86 at its outer end, and this ball is socketed for universal movement in a suitably recessed part 87 of the stationary or end bracket 81, the socket being completed by a plug or disc 88 in which is seated a spring-and-presser assembly 89 to take up play, the disc being held in its seat by a set screw 90 threaded into the end bracket 81.

The other end bracket 82 (Fig. 5) is recessed 30 and has one side 91 provided with a substantially square opening confronting the adjacent end of the handle 80. The rear adjoining side of the end bracket opens toward the door and a passage 92 leading through the latter to a point opposite site the arm 72 on rod 60 (Fig. 5). Interiorly of the recessed end mount 82 are a pair of screw-receiving bosses 93 and a seating boss 94 having a vertical side-opening slot 95 to receive a pivot pin 96 (see also Fig. 7) which is extended between a pair of spaced offset ears 97 extended laterally from a trip arm 98. This arm 98 has one (left) end portion enlarged and bifurcated, as at 99, each of the bifurcations 100 being rolled back around a link pivot pin 101 on which is mounted, between the bifurcations, one end of 45 an operating link 102. This link extends through the passage or hole 92 in the door and connects at its inner end 103 with the hooked part 73 of the arm 72 on operating rod 60. A screw and washer 104 on boss 94 prevents the pivot pin 96 from unseating.

Referring to Fig. 5, it will be observed that the innermost (right) corner portions of the square side opening 91 of the recessed end mount 82 are routed or rounded-out to provide recesses 105 into which fit respectively one of each of a pair of spaced trip pins 106 extended in an axial sense from the left end of the main handle 80 (Figs. 4, 5, 6,) and these pins 106 extend far enough 55 into the end mount to lie behind each of the rolled ends 100 of the bifurcations. It will be recalled that the rod 60 is urged into a normal position by its spring 66, and thus, as viewed in Fig. 5, this rod and the arm 72 will tend to move 60 toward the right, pulling the trip arm 98 toward the right (the same pivoting about the pin 96) so that both of the rolled ends 100 of the trip arm 65 are close against the pins 106.

It will be recalled further that the right-hand 70 end of the handle 80 is universally joined to its end mount or bracket 81 by a ball and socket connection 86-87, so that the handle 80 is free to be twisted from its normal position of Fig. 6 into either of the two dotted line positions there 75 shown, and it will be apparent that one of the

two trip pins 106 will provide a pivot while the other pin will move back against its corresponding rolled end part 100 on the trip cam, and the latter will be moved toward the left thus pivoting the operating rod 60 through the link 5 102 and arm 72.

However, in addition to the two different operating movements just described in view of Fig. 6, there is still a third degree of movement illustrated in Fig. 4, where it will be seen that if the handle 80 is pulled outwardly of the door to the dotted line position, both of the pins 106 will bear against the rolled ends 100 of the trip arm, and the rod 60 will again be rotated, and it should be observed that no matter which of the three 15 possible movements is imparted to the handle 80, the movement of the lever arm 102 and rod 60 is always the same, that is, clockwise, as viewed in Fig. 4.

It will thus appear that I have provided a 20 latch and operating mechanism therefor in accordance with the several objects hereinabove set forth, and particularly a latch comprising a housing having a bolt pivoted in a sliding carriage against the tension of a positioning spring, 25 the carriage being positioned also by a spring, so that the bolt tends at all times to be in effective position. This bolt may either be pivoted or slid into ineffective position.

The novel latch further includes a pivoted locking member movable with the bolt carriage and normally spring-urged into a position to block 30 pivotal movement of the bolt, together with a handle having several degrees of freedom for releasing movement and operable to move the lock 35 member into ineffective position whichever way the handle is moved.

The foregoing particularly described device sets forth only one embodiment of the invention, and it is expressly provided that the appended 40 claims are intended to embrace any and all modifications, rearrangements, and variations or combinations of the invention defined by the annexed claims, and coming within the spirit of the invention.

Having thus described my invention, what I 45 claim as new and desire to protect by Letters Patent is:

1. Latch operating means including an elongated handle disposed between a pair of end brackets and having at one axial end a ball-and-socket engagement with one of said brackets, the other of said brackets having a chamber opening onto the opposite axial end of said handle, a trip lever pivoted in said bracket chamber and having a pin-engaging portion disposed opposite the adjacent end of said handle and movable in a direction transverse to the long axis of the handle toward and away from a particular side of said chamber, said handle having a pair of spaced pins extended axially into said bracket chamber between said pin-engaging portion and said particular side of the chamber, whereby said handle may be pivoted in opposite directions substantially about its own long axis to cause one 55 of said pins to bear against said pin-engaging portion of the trip lever while the other one of said pins provides a fulcrum against said particular side of the chamber, said handle, in addition, being movable laterally of its said long axis to cause one or both of said pins to bear against said pin-engaging portion of said trip lever and move the latter in a direction away from said particular side of the chamber, said 60

trip lever being adapted for operative connection with a latch.

2. A combination latch-operating and handle means including a substantially elongated handle member, a pair of end mounts adapted for mounting on a door or the like at opposite ends of said handle, means in one of said end mounts providing universal pivotal mounting for said handle, means in the opposite end mount including a lever operating member mounted for pivotal movement in the same plane as that upon which said end mounts are themselves mounted, and spaced means projecting from the axial end of said handle corresponding to said last-mentioned opposite end mount and each providing a fulcrum for pivotal movement of said handle in opposite directions and each operatively engageable with said pivoted lever operating member to move said lever member when said handle is pivoted in one of two opposite directions about the other of said axially extending means as a fulcrum, said handle being movable to effect engagement of all of said axially extending means with said pivoted member to operate said lever when said handle is moved in a direction away from the aforesaid plane.

3. A combination handle and latch-operating device including a substantially elongated handle member and means at its opposite ends including end mounts mounting the same for universal movement upon a door surface or the like, latch-operating means in one of said end mounts and including a pivoted operating member therein, together with means arranged on the end of said handle which corresponds to said last-mentioned mount and constructed for engagement with said pivoted operating member to actuate the same and said latch-operating means when said handle is pivoted in opposite directions toward said door surface and also when said handle is pulled in a direction away from said surface.

4. A combination handle and latch-operating structure including spaced end mounts adapted for mounting on a door or the like, a handle member disposed between said end mounts and having universal pivotal support on one of the same, latch-operating mechanism in the opposite one of said end mounts and including a pivoted operating element therein having its pivotal axis substantially parallel to the surface of the door upon which the end mounts are mounted, and spaced axially extending means on the end of said handle corresponding to said opposite end mount and arranged to engage and pivot said pivoted operating element when said handle is turned in either of two opposite directions relative to the aforesaid surface and also when said handle is pulled in a direction away from said surface.

60 5. A combination handle and latch-operating structure including an elongated handle member mounted at one end for universal movement on a door and having an end bracket mounted at its opposite end, latch-operating mechanism in said end bracket and including a pivoted operating element and means at said opposite end of said handle engageable with said bracket to provide a fulcrum when said handle is pivoted in opposite directions toward said door and operatively engageable with said pivoted element to actuate said latch-operating mechanism, said means also being operatively engageable with said pivoted element to actuate the same when said handle is moved in a direction away from said door.

6. A latch-operating handle structure including a pair of spaced end brackets adapted for mounting on a door or the like, a handle disposed between said brackets and having a ball and socket mounting at one of its ends with a corresponding one of said brackets, the opposite said bracket having a trip arm and a movable operating element therefor, together with spaced means at the end of said handle corresponding to said opposite bracket, said spaced means each providing a fulcrum respective to the other cooperably with said opposite bracket, whereby said handle may be pivoted in opposite directions about its long axis between said brackets, as well as in a direction laterally away from said axis to effect actuation of said movable operating member by said spaced means.

7. A combination handle and latch-operating structure including an elongated handle member and bracket means at one end thereof mounting the same for pivotal movement in opposite directions about the long axis of the handle and also for pivotal movement at said one end about an axis disposed laterally of the aforesaid long axis, and a second bracket means at the opposite end of the handle and having arranged therein a movable latch-operating member, said handle having means at its end adjacent said second bracket means operatively engageable with said latch-operating member to actuate the latter when said handle is moved in a direction about any of the pivotal axes aforesaid.

8. A combination handle and latch-operating structure including an elongated handle member provided with bracket means at its opposite ends supporting said handle on a door or the like and mounting said handle for rocking movement in opposite directions about its long axis and also for pivotal movement in a direction away from said door in the region of a particular one of its ends, the end thereof opposite said particular end being provided with fulcrum engageable with the corresponding bracket member to provide a pivoting fulcrum whenever the handle is rocked about its long axis as aforesaid, said last-mentioned bracket means being provided with a pivoted latch-operating member arranged to be operatively engaged and pivoted by said fulcrum means whenever said handle is rocked or pivoted as aforesaid.

9. A latch-operating handle including a substantially elongated handle member provided with bracket means at its opposite end for mounting the same upon a door or the like, said handle having pivotal support at one of its ends in the corresponding bracket means whereby the handle may be moved in opposite directions about an axis substantially parallel to that of the handle and also in a direction substantially transverse to said last-mentioned axis, the opposite end of said handle having a pair of axially extended spaced pin members opposite ones of which provide pivotal bearing engagement with the said corresponding bracket means when said handle is rocked in opposite directions as aforesaid, said last-mentioned bracket means having a movable latch-operating member arranged therein and engaged for operation by one of said pin members whenever said handle is rocked, both of said pin members operatively engaging said latch-operating member when said handle is pivoted about said transverse axis.

10. A latch-operating handle including a substantially elongated handle member having a

ball and socket mounting in a bracket member at one end thereof and permitting substantially universal freedom of movement for the handle, a bracket member adapted to be mounted at the 5 opposite end of said handle and having a pivoted latch-operating member arranged therein for pivotal movement about an axis extending in a transverse sense to the long axis of said handle, said opposite end of the handle having a pair of 10 spaced pin members extending in an axial direction therefrom into the corresponding bracket member, opposite ones of said pin members having bearing engagement with the corresponding bracket member when the handle is rocked as 15 aforesaid in either of its opposite directions whereby the other pin member of the pair is moved into operative engagement with said pivoted latch-operating member to actuate the latter, both of said pin members operatively engaging 20 said latch-operating member when the handle is pivoted about the aforesaid transverse axis.

11. A combination handle and latch-operating structure including a substantially elongated handle having a bearing member extended in an 25 axial sense from a particular end thereof, said

bearing member having bearing support for universal movement in a bracket member adapted for attachment to a door or the like, a second bracket member arranged at the opposite end of said handle and likewise adapted for mounting 5 on a door, said last-mentioned bracket member having a latch-operating element mounted therein for pivotal movement about an axis extending in a transverse sense to the long axis of said handle, said handle having a pair of 10 spaced extensions projecting in an axial sense into second bracket member and each operatively engageable with said latch-operating member to pivot the latter by pivotal movement of said handle about an axis substantially parallel 15 with the pivotal axis of said latch-operating member, one of said spaced extensions having bearing engagement with said second bracket member whenever said handle is rocked about an axis substantially parallel to the long axis 20 of said handle, while the opposite extension of the pair is moved in a direction for operative engagement with said latch-operating member to actuate the latter.

LLOYD ANDERSON. 25
